UNITED STATES PATENT OFFICE.

WALTER P. ELLISON, OF LYONS, KANSAS.

COLT-WEANER.

1,072,591.

Specification of Letters Patent.

Patented Sept. 9, 1913.

Application filed March 3, 1913. Serial No. 751,857.

To all whom it may concern:

Be it known that I, WALTER P. ELLISON, a citizen of the United States, residing at Lyons, in the county of Rice and State of Kansas, have invented certain new and useful Improvements in Colt-Weaners, of which the following is a specification, reference being had to the accompanying drawings.

10 This invention relates to new and useful improvements in colt or calf weaners and has for its object to provide a device of this character which may be quickly and readily applied to a halter and which will be most effective in carrying out the objects for which the same is designed.

15 A further object of the invention resides in providing a device which is formed of a flexible nose band to which is attached a 20 pronged plate and a still further object resides in providing means on the nose band for attaching the same to the nose strap of a halter.

25 A still further object of the invention resides in providing a device which is simple and durable in construction, inexpensive to manufacture and one which will be very efficient and useful in operation.

With these and other objects in view, 30 the invention consists in the novel features of construction, combination and arrangement of parts as will be hereinafter referred to and more particularly pointed out in the specification and claims.

35 In the accompanying drawing forming a part of this application, Figure 1 is a perspective view showing my device applied to a halter; Fig. 2 is a side elevation of the device; and Fig. 3 is a vertical section there- 40 through.

In describing my invention, I shall refer to the drawing in which similar reference characters designate corresponding parts throughout the several views and in which 45 1 indicates a halter of the usual or any preferred type, the nose strap 2 and the cheek straps 3 of which are engaged with the usual metal squares or connecting members 4'. In many halters, rings are used in place

50 of squares which are shown in my drawing, but this is immaterial, as this part of the device forms no essential part of the invention.

55 My invention contemplates the provision of a weaning device particularly adapted for attachment to the nose strap of a halter,

and to this end, the nose band or the like 4 is provided, the same being formed of flexible material, preferably leather. This band is of considerable width, tapering from 60 its center toward the ends and bent to conform to the curvature of an animal's nose and riveted or otherwise secured to the outer face of this band 4 is a plate 5, formed preferably of metal. This plate 5 is, of course, 65 bent arcuately and retains the flexible band 4 in an arcuate position. This plate 5 has the upper and lower edges thereof also spaced from the upper and lower edges of the band 4 and tapers somewhat toward its 70 ends, and the ends of said plate terminate some distance from the ends of the band 4 so that the latter are flexible so as to be readily applied to use. Struck up from the plate 5 throughout the face thereof, are the 75 tongues 6. These tongues are substantially triangular in design and are bent to extend at substantial right angles to the face of the plate 4, thereby forming prongs thereon.

80 This device, as stated above, is particularly adapted for use in connection with a halter and in order to provide means for the attachment thereof to a halter, I provide the flexible connections 7 which are detachably engaged with the band 4 at the central portion thereof adjacent its upper edge and at its ends as clearly shown in the drawing. The flexible connection at the central portion of the band is adapted to be engaged 85 with the central portion of the nose band 2 of the halter, while the flexible connections at the ends of said band 4 are adapted for engagement with the squares 4' of the halter, it being understood that these latter 90 flexible connections are equally well adapted 95 for engagement with any form of engaging means. When so applied to the halter and the halter properly applied to the head of an animal, it will be seen that this band 100 will, extend flatly over the nose of the animal to a point immediately adjacent the mouth and as the prongs will extend outwardly therefrom, it is obvious that sucking will be prevented.

105 From the foregoing it will be seen that I have provided a simple, inexpensive and efficient means for carrying out the objects of the invention and while I have particularly described the elements best adapted to 110 perform the functions set forth, it is obvious that various changes in form, proportion

and in the minor details of construction may be resorted to without departing from the spirit or sacrificing any of the principles of the invention.

5 Having thus described this invention, what I claim is:—

1. A colt or calf weaner comprising a flexible nose band tapering from its center toward its ends, a plate applied to the outer 10 face thereof and bent arcuately to retain the band in rigid arcuate position, the ends of said plate terminating in advance of the ends of the band to permit flexibility at the latter points, said plate also tapering from 15 its center to its ends and having the upper and lower edges thereof spaced from the upper and lower edges of the band, prongs formed on said plate, and means to attach said band to a halter.

2. A colt or calf weaner comprising a flexible nose band, a plate secured to the outer face thereof and bent arcuately to retain said band in rigid arcuate position for application to the nose of an animal, the ends of said plate terminating in advance of the 25 ends of the band to permit flexibility at the latter points, prongs struck up from said plate, and flexible connecting means engaged with the ends and the upper central portion of said band to secure the same to the nose 30 band of a halter.

In testimony whereof I hereunto affix my signature in the presence of two witnessess.

WALTER P. ELLISON.
